UNITED STATES PATENT OFFICE.

WILLIAM HANFORD KING, OF LITTLE SILVER, NEW JERSEY.

LETTER AND BILL FILE.

SPECIFICATION forming part of Letters Patent No. 355,614, dated January 4, 1887.

Application filed September 18, 1886. Serial No. 213,931. (No model.)

To all whom it may concern:

Be it known that I, WILLIAM HANFORD KING, of Little Silver, in the county of Monmouth and State of New Jersey, have invented 5 a new and Improved Letter and Bill File, of which the following is a full, clear and exact description.

My invention relates to a file adapted for use in filing letters, invoices, bills of lading, 10 receipts, advertisements, ships' manifests, or other papers or documents, and has for its object to provide a simple inexpensive file of this character, on which the papers may be quickly placed for reference, and from which 15 they or any of them may be as easily removed, the file also allowing the papers on it to be bound at any time, as may be desired or necessary.

The invention consists in certain novel features of construction and combinations of parts 20 of the file, all as hereinafter fully described and claimed.

Reference is to be had to the accompanying drawings, forming a part of this specification, 25 in which similar letters of reference indicate corresponding parts in both the figures.

Figure 1 is a plan view of my improved letter and bill file, with the hinged head-piece and its pins swung upward and backward to 30 allow papers to be placed on the file or to be removed therefrom; and Fig. 2 is an edge view of the file, showing the head-piece swung down or over into normal position for holding papers on the file, and with its other position 35 indicated in dotted lines, a few letters or papers also being shown on the file.

The back or base A of the file has fixed to its lower or inner edge a bar or foot-piece, B, in which the parts C C of the file wires or pins 40 are fixed so as to project about parallel with the base and a short distance from it. The other parts, D D, of the file-pins are fixed to a head-piece, E; which has lugs e e, which pass between lugs a a on the base A of the file, and 45 pins F, passed through the lugs e a a at each side edge of the top or head of the base, form, with the lugs, hinges on which the head-piece E and its pins D D may be swung over upward and backward, as shown in full lines in Fig. 1 and 50 in dotted lines in Fig. 2.

Projections or studs e' on the head-piece lugs e are adapted to strike the inclined back edges of the base-lugs a, to limit the swinging movement of the head-piece in either direction, but more especially when the head-piece 55 is swung down forward to close the file. A spring, G, fixed at one end to the base A, acts by its free end on the two right-angularly disposed faces of the back end of one of the head-piece lugs to hold the head-piece in either of 60 its two positions—in other words, to hold the file open or closed.

The meeting ends of the two parts C D of the file-pins are preferably beveled to cause the ends of the pins to exactly coincide when 65 the file is closed and allow the letters, bills, or papers H placed on the file to be moved freely along the pins over or past the joints of the ends of the pins, as may be required in examining or adjusting the papers. 70

I provide a retainer to hold the papers H snugly together on the file-pins. This retainer is preferably an angular plate, I, the face or part i of which rests on the papers to hold them together, while the other face or part, i', 75 of the retainer lies flat upon the base A of the file. When it is desired to extend the retainer above or beyond the file-pins, the part i of the retainer will have open slits or slots e e in its edge to allow the upper part, D, of the file-pins to rise from the base A as the head-piece E of the file is swung over backward with its pins D; but, if desired, the part i of the retainer need not extend quite to the file-pins, as indicated by the dotted line i' in Fig. 2 of 85 the drawings.

The base A is provided with a slot, J, in which is fitted loosely a bolt, K, which has a head, k, at the back of the base, and is fitted on its threaded end with a set-screw, L. 90 When the screw L is loosened, the retainer I may be adjusted anywhere along the base of the file to cause its part i to bear on the papers thereon and hold them snugly together on the file-pins and to the base-piece B of the 95 file.

To place the papers H on the file, the head-piece E will be swung over backward with its pins D, as in full lines in Fig. 1 and in dotted lines in Fig. 2, and when the retainer I is slid 100

along clear of the pins C the papers will be stuck on these pins. The head-piece will then be swung over forward to close the ends of the pins D onto the ends of the pins C to lock the 5 papers onto the file, and the retainer I will then be slid down onto the papers and tightened by the set-screw to hold the papers together, as shown in Fig. 2 of the drawings. When the set-screw L is loosened, the retainer and papers may be moved anywhere 10 along the base of the file.

To remove an old letter, bill, or paper from the file, the retainer will be loosened, and it and all the papers above the one wanted will 15 be slid upward to the parts D of the pins, and the head-piece will then be swung over to open the file and allow the desired paper to be taken from the pins C, and when the file is again closed by swinging over the head-piece 20 all the papers left on it will be arranged in order as before and may be held snugly together by the retainer.

To allow all the papers on the file to be bound at any stated times, I purpose making 25 the pins D hollow, as shown in Fig. 1. To allow the ends of a lacing-cord to be passed through these pins after the papers are moved onto the pins and when the papers are withdrawn together, the cord will be looped through 30 them, ready for tying, to complete the binding of the papers; or, instead of making the pins D hollow, as above described, I may form eyes d in them, near their points, and through which eyes the opposite ends of the binding-cord 35 may be passed after the papers are slipped onto the pins D and the file is opened, and when the papers are withdrawn from the pins the ends of the binding-cord may be pulled from the pin-eyes and be tied at the back of 40 the package of papers through which the cord had been laced as the papers were withdrawn from the pins.

It will be noticed from Fig. 2 of the drawings that the head-piece E does not project behind or beneath the back of the base A of the 45 file, whether the file be open or closed; hence papers may be placed on or taken from the file while it lies flat on a desk or table or against a side wall. Furthermore, the extension of

the head-piece E clear across the head of the 50 file affords a bed across which the papers may lie smoothly should they be turned over backward in using the file, and the front edge of the base-piece B affords a like support on which the papers may rest smoothly.

I show the file made with two pins or pairs of coinciding pins, C D; but one pair or three or more pairs of these pins may be used, as the size of the papers to be filed may require. If preferred, the head-piece may be pivoted 60 to the base A by ordinary butt-hinges.

Having thus fully described my invention, what I claim as new, and desire to secure by Letters Patent, is—

1. A letter and bill file comprising a base, 65 A, fixed pins C, supported therefrom and about parallel thereto, a hinged head-piece, E, and pins D, fixed therein and coinciding with the pins C when the file is closed, substantially as shown and described.

2. The combination, in a letter and bill file, of a base, A, a foot-piece, B, fixed thereto, pins C, fixed in the foot-piece, a head-piece, E, hinged to the base A, and pins D, fixed in the head-piece and coinciding with the pins C 75 when the file is closed, substantially as shown and described.

3. The combination, in a letter and bill file comprising a base, A, and hinged head-piece E, and pins D in part E, of stop-studs e' on the 80 head-piece and a spring, G, holding the head-piece in position with the file either open or closed, substantially as shown and described.

4. A letter and bill file comprising a base, 85 A, foot-piece B, fixed pins C, a hinged head-piece, E, and pins D therein, coinciding with the pins C when the file is closed, and said pins D made hollow to allow binding of the papers on file, substantially as shown and described.

5. In a letter and bill file, the combination, with the base A, slotted at J, and the file-pins C D, of a retainer, I, and a bolt and set-screw, K L, substantially as shown and described.

WILLIAM HANFORD KING.
